United States Patent Office.

CHARLES B. HATFIELD, OF PHILADELPHIA, PENNSYLVANIA, ASSIGNOR TO HIMSELF, HORACE B. HEILMAN, JOSEPH WILLCOX, AND HENRY B. WILLCOX.

Letters Patent No. 100,621, dated March 8, 1870.

IMPROVEMENT IN PAPER-BOX MACHINES.

The Schedule referred to in these Letters Patent and making part of the same

I, CHARLES B. HATFIELD, of Philadelphia, county of Philadelphia, State of Pennsylvania, have invented a Machine for Forming Paper Boxes and Lids for the same, of which the following is a specification.

Nature and Objects of the Invention.

My invention consists in certain mechanism, fully described hereafter, for forming paper boxes and lids for the same, either with or without flanged ends.

Description of the Accompanying Drawings.

Figure 1, (Sheet 1,) is a longitudinal vertical section of the machine.

Figure 2, a plan view.

Figures 3, 4, and 5, enlarged views of the expanding head upon which the boxes and lids are formed.

Figure 6, (Sheet 2,) a transverse vertical section of the machine on the line 1-2, fig. 1.

Figure 7, an enlarged view of a portion of the machine;

Figure 8, a transverse section on the line 3-1, fig. 1; and

Figures 9, 10, and 11, detached views drawn to an enlarged scale, and illustrating portions of the machine.

General Description.

The frame of the machine consists of a platform, A, which rests upon suitable legs *a*, and in standards B B', secured to the top of this platform, turns the main driving shaft C, furnished at one end with a driving pulley, *b*, to which motion is communicated from an adjoining line of shafting.

The shaft C is hollow for the greater portion of its length, and terminates at its inner end in what I have termed an expanding head, D, the latter consisting of three main elements, namely, of a disk, *c*, permanently secured to the shaft, of a movable disk, *d*, which is attached to a rod, *d'*, arranged to slide through the shaft, and of four or other suitable number of segments, *f*, which form the expanding portion of the head. (See figs. 3, 4, and 5.)

The rod *d'*, to which the disk *d* is attached, is connected at its opposite end to a sleeve, *e*, which slides upon the driving shaft, the connection between the rod and sleeve being made through a longitudinal slot, *e'*, of the shaft, which permits the required sliding motion of the several parts.

The sleeve *e* is grooved to receive the forked end of a lever, *F*, which is hung to a transverse spindle, *G*, furnished at one end with an operating arm, *G'*; and the lower arm of the said lever projects through an opening in the platform A, and is connected to a spiral or other spring, *g*, which tends to retain it in the position shown in fig. 1, and to consequently maintain the disk *d* of the expanding head in contact with the disk *c*.

The lever *F* is also connected, by means of a rod, *g*, beneath the platform A, with another lever, *H*, which is hung to a standard or bracket, *h*, at the opposite end of the machine, for a purpose described hereafter.

The segments *f* of the expanding head D are in the present instance four in number, being secured to dovetailed tongues *i*, which radiate from the center of the disk *d*, and which are adapted to and arranged to slide in dovetailed grooves formed in the said disk. (See fig. 5.)

The sliding of these tongues and their segments from or toward the center of the disk effects the required expanding or contracting of the head, and is accomplished by links *j*, which connect each of the said tongues with a sleeve, *J*, which slides upon the driving shaft, the said sleeve being operated through the medium of rods, *j* and *j'* by a lever, *K*, hung to the standard B'.

The segments *f* are bound together by a rubber band or spring, *k*, and a spiral spring, *k'*, on the driving shaft bears against the sleeve *J*, and tends to force it towards the head D, the object of these springs being merely to take up the lost motion of the several parts so as to insure the proper expanding and contracting of the head.

I is a standard secured to the platform A, in which slides a horizontal rod, *K'*, in line with the driving shaft, a disk, *l*, being secured to one end of this rod, while on the opposite end is a spiral spring, *l'*, which tends to maintain the said disk in the position shown in fig. 1.

Above this rod, and supported by the same standard I, is a tube or cylindrical reservoir, M, in which are placed the circular pieces of paper or straw board which are to form the bottoms of the boxes, a plunger, *m*, bearing against the pieces with a constant pressure, which is exerted by a cord and weight, *m'*, attached to the plunger rod *m'*, the latter sliding in a post or standard, *N*, of the platform A.

A vertical plate, P, (figs. 1 and 6,) is secured to the front of the reservoir M, and in this plate are formed two openings, one for the passage of the pieces of straw board from the reservoir, and the other for the sliding disk *l*, the latter opening being of the smallest diameter.

A sliding frame, Q, at the front of the plate P, is guided partly by lugs *p* *p'* of the latter, and partly by a rod, *p'*, which projects downward through an opening in the platform A, a spring, *p''*, upon this rod retaining the frame in the elevated position shown in figs. 1 and 6.

To the frame Q is secured a vertical pusher-bar, S, a portion of which, on the side towards the reservoir, is cut away so as to form an abrupt shoulder, *r*, (fig. 7,) the latter, when the frame is depressed by means

of a handle, r^1 , detaching the circular pieces from the reservoir one at a time, and pushing them downward until brought opposite to the disk l , they being held in this position when the pusher-bar is raised by a shoulder, r^2 , of the plate P . (See figs. 6 and 7.)

A lever, R , is hung to the platform A at a point beneath the expanding head D , and is arranged to be operated by a treadle, s , beneath the platform, and is so acted on by a spring, s^1 , that its forked arm s^2 is maintained almost or quite in contact with the head.

To this forked arm s^2 is hung the spindle of the roller U , which has movable flanges t and t' arranged to slide upon the spindle, but held against the roller by spiral springs t^1 .

The upper arm of the lever H above referred to is tubular, and contains a spring-latch, T , which is connected by means of a rod, T' , to an arm, u , of a rock-spindle, V , which turns in suitable bearings beneath the platform A , another arm, u' , at the opposite end of this rock-spindle, being connected by a rod, u^1 , to the treadle s , so that, on depressing the latter, both the lever R and latch T may be operated.

The latch T remains stationary during the first part of the motion of the lever R , in consequence of the lost motion in a slot, r , of the rod T' , the object of which arrangement will be described hereafter.

A spindle, W , which receives its motion either by means of bevel-gear from the driving shaft, or directly from the line shaft above, turns in the standard B , and is furnished with two eccentrics, w w' , each of which imparts a rapid vibrating movement to a curved finger, z , (see fig. 11,) the object of these fingers being to turn over and fold down a portion of the thin paper covering of a box, in a manner which will be fully described hereafter.

Operation

It should be understood, before proceeding further, that the above machine is intended principally for forming cylindrical paper boxes, either with or without flanged ends, the cylindrical body of the box of rough straw board, and the disk of the same material, which is to form the bottom of the box, being made by previous operations and fed to the machine, so that the work of the latter is limited to connecting the body and bottom of the box together by means of an outside covering of thin paper, and thus finishing the box.

A rapid rotary motion having been imparted to the driving-shaft and its expanding head D , and to the spindle W , by which the fingers z z' are operated, one of the attendants, as a preliminary operation, depresses the treadle s , and thereby throws back the lever R and its flanged roller U from contact with the expanding head. The same attendant then slips one of the cylindrical box-bodies, marked x in fig. 10, over the head D , and immediately expands the latter, so as to firmly hold the box-body by means of the lever K .

The lever R being still held back, the next operation is to depress the frame Q , so that its pusher-bar S may detach one of the straw-board disks from the reservoir M , and push the same downward until the shoulder r^2 retains it in a position directly in front of the disk l . This having been accomplished, the frame Q is released, and is permitted to spring upward to its original position, the arm G' being then depressed by a second attendant until both the levers F and H have been moved to the positions indicated by dotted lines in fig. 1, thus throwing the latch T against the end of the rod K' , and moving the disk d outward from the expanding head until it is brought in contact with the circular piece of straw-board y , against the opposite side of which bears the disk l .

It should be explained before proceeding further that both of the disks d and l are furnished with pointed projections or teeth, arranged in circles, for the purpose of retaining the straw-board disk firmly between

them, and that each disk has a circular groove directly opposite to the row of teeth in the other disk, so as to permit the straw-board to be penetrated or indented, and held by the teeth, without wounding the latter.

The disks d and l , with the piece of straw-board held between them, are next moved toward the expanding head D by an upward movement of the arm G' , the lever F drawing back the rod d' , and the latch T of the lever H pushing the rod K' before it. This last movement, as will be observed in fig. 9 and by dotted lines in fig. 10, brings the disk which is to form the bottom of the box against the body z of the same, a portion of the disk projecting over the body, as plainly shown in the drawing, to form the desired flange. This movement also pushes the bottom y against the body of the box with such pressure as to move the latter further onto the expanding head, this intimate contact insuring a tight joint between the bottom of the box and the body of the same.

One of the attendants now places the end of a strip of the thin covering-paper (which has been previously cut to the required width and length, and brushed with paste or glue upon one side) against the revolving box-body on the expanding head, care being taken that this strip of paper shall project over each end of the box and over the bottom y of the same. The revolving of the head and box will wind the strip of paper upon the latter, and all that remains to be done is to press this covering against the body z and to turn the edges over, so as to secure the bottom, and finish the upper edge of the box. This is effected by means of the flanged roller U and fingers z z' , the pressure upon the treadle s being relieved, so as to permit the roller to regain its original position in contact with the head. The flat central portion of the roller presses against and finishes the sides of the box, and the flange t yields sufficiently to permit the introduction between it and the roller of the flange of the box, so that the covering is turned over and pasted down upon the latter in the manner clearly shown in fig. 9. The flange t' in the mean time turns the other projecting portion of the covering-material over the edge of the box, at right angles to the same, as seen in fig. 9, and the fingers z z' complete the operation, by turning in and folding this portion of the cover against the inside of the box. This finishes the box, and in order to withdraw it from the head the disk l must first be returned to its original position, and the flanged roller U thrown back. These movements are effected simultaneously by depressing the treadle s , the lever R being first thrown back, while the arm u of the rock-spindle V is passing through the slot r of the arm T' , the latter then being depressed, and drawing back the latch T from contact with the end of the spring-rod K' , which will permit the said spring-rod and its disk l to regain their original position, fig. 1.

All that now remains to be done is to contract the head D by means of the lever K and devices connected therewith, in order to permit the withdrawal of the finished box, the operation of forming the succeeding boxes being continued in the same manner.

The method of operating the machine to form the lids of the boxes is precisely the same as that before described, the lids being, in fact, nothing more than short boxes.

Claims.

1. An expanding head, D , for paper-box machines, consisting of three main elements, namely, of a disk, e , which forms the permanent portion of the head, of segments f , arranged for radial adjustment upon the said disk, and of a movable disk, d , the whole being arranged in respect to each other and for joint operation, substantially as herein described.

2. The said head D arranged to be expanded and contracted by means of a sleeve, J , on the driving-

shaft, and links i , connecting the same with the segments f , the said sleeve being operated by the devices herein described, or by any equivalents to the same.

3. The said expanding head acted on by springs k and l , substantially in the manner described.

4. The combination, substantially as herein described, of the said expanding head with the double-flanged roller U .

5. The combination, substantially as herein described, of the sliding disk d of the said expanding head with a sliding disk, l , attached to a spring-rod, K .

6. The combination, substantially as herein described, of the said expanding head with the vibrating fingers z .

7. The roller U , having at each end a movable flange, t or t' , acted on by springs t , substantially as and for the purpose specified.

8. The levers F and H , connected by a rod, g , and acted on by a suitable spring, or any device equivalent to these levers whereby the disks d and l may be operated, substantially in the manner described.

9. The combination of the rock-shaft V , its arms u and u' , the connecting-rods T' and T'' , and the treadle s , or any mechanism equivalent to the same, by means

of which the throwing back of the lever R and with drawing of the spring-latch may be effected simultaneously.

10. The spring-latch T , arranged to operate the spring-rod K and its disk l , substantially in the manner described.

11. The combination of the reservoir M , shoulder r , rod K , and pusher-bar S with its shoulder r , all arranged and operating as specified.

12. The disks l and d , each furnished with a circular groove and with pointed projections or teeth, arranged to enter said grooves, substantially as herein set forth.

13. The vibrating curved fingers z , operating substantially in the manner described, for the purpose of turning in the covering of thin paper, in finishing the edge of a box.

In testimony whereof I have signed my name to this specification in the presence of two subscribing witnesses.

CHARLES B. HATFIELD.
